US0D1087801S

(12) **United States Design Patent** (10) **Patent No.:** **US D1,087,801 S**
(45) **Date of Patent:** **** Aug. 12, 2025**

(54) **SAMPLE COLLECTION DEVICE**

(71) Applicant: **Siro Diagnostics, Inc.**, San Diego, CA (US)

(72) Inventors: **Cedric Bathany**, Vista, CA (US); **Michael David Jacobson**, San Diego, CA (US); **Clint Sever**, San Diego, CA (US)

(73) Assignee: **Siro Diagnostics, Inc.**, San Diego, CA (US)

(**) Term: **15 Years**

(21) Appl. No.: **29/861,512**

(22) Filed: **Nov. 30, 2022**

(51) LOC (15) Cl. **24-02**

(52) U.S. Cl.

USPC **D24/224**; D24/216

(58) **Field of Classification Search**

USPC D24/107, 108, 115, 120-123, 130, 216, D24/224; D9/501, 519, 537, 549, 723,

D9/724

CPC A61B 10/0045; A61B 5/14; A61B 5/15; A61B 10/0051; A61B 10/0048; A61B 10/0058; A61B 10/0064; A61B 10/0096; B01L 3/5023; B01L 3/50; B01L 3/505; B01L 3/508; B01L 3/52; B01L 3/523

(57) **CLAIM**

The ornamental design for a sample collection device as shown and described.

DESCRIPTION

FIG. 1 is a top, front, right side perspective view of a sample collection device;

FIG. 2 is a bottom, rear, left side perspective view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front elevation view thereof;

FIG. 8 is a rear elevation view thereof;

FIG. 9 is a cross-section view thereof taken along line 9-9 of FIG. 7; and,

FIG. 10 is a cross-section view thereof taken along line 10-10 of FIG. 7.

The broken lines in the drawings are for illustrative purposes only and form no part of the claimed design.

1 Claim, 6 Drawing Sheets
